UNITED STATES PATENT OFFICE.

WORTHY CHANNING BUCKNAM, OF GENEVA, OHIO, ASSIGNOR TO THE GENEVA AUTOMOBILE AND MANUFACTURING COMPANY, OF GENEVA, OHIO, A CORPORATION OF OHIO.

GAS-BURNER.

SPECIFICATION forming part of Letters Patent No. 739,584, dated September 22, 1903.

Application filed March 28, 1902. Serial No. 100,454. (No model.)

To all whom it may concern:

Be it known that I, WORTHY CHANNING BUCKNAM, a citizen of the United States, residing at Geneva, in the county of Ashtabula and State of Ohio, have invented a certain new and useful Improvement in Gas-Burners, of which the following is a full, clear, and exact description, reference being had to the accompanying drawings.

10 The object of this invention is to provide a very efficient gas-burner which while being cheap in construction and very durable shall properly distribute the gas and shall not back-fire—that is, catch fire in the admission-tube.

15 The burner, though advantageous in various installations, is particularly designed for burning vaporized gasoline in an automobile.

My burner consists, primarily, of a continuous coiled pipe perforated on its upper side 20 and on its lower side intercepting a cross-pipe, which conveys the gas to the coil. I am aware that it has heretofore been proposed to use a spiral pipe with the gas entering one end thereof; but this is very unsatisfactory in 25 not giving even distribution, there being too much pressure at the end where the gas enters and too little pressure near the opposite end. I know also that it has been proposed to provide a mixing-pipe surmounted by nu- 30 merous straight disconnected cross-pipes. My burner is an improvement over this also not only in its much greater ease of construction and durability, but because, owing to the different portions of the burner-pipe being all 35 in continuous longitudinal communication, the gas-pressure in all the different sections becomes equalized and the burner burns evenly throughout. This equalization of pressure has been found to be very efficient in 40 preventing the flame snapping back into the admission-tube. I provide also a very simple means for carrying the burner. This and the particular embodiment of the burner hereinafter described are comprehended 45 within my invention.

The drawings clearly illustrate the invention, Figure 1 being a plan, and Fig. 2 a sectional side elevation.

In the drawings, A designates the burner-pipe. This is a continuous coil, being preferably a spiral closed at each end by plugs a. On the upper surface of the burner-pipe are numerous burner-holes a'.

B represents the distributing-pipe, which is a plain tube plugged at its ends by plugs b and has its upper surface intercepting the lower surface of the spiral. This is very conveniently accomplished in practice by milling across the spiral a concavity of a radius equal to that of the exterior of the pipe B and 50 milling across the pipe B concavities of a radius equal to the exterior of any portion of the spiral pipe, these latter cavities being curved longitudinally according to their position. Openings are thus produced in the 55 spiral and the distributing-pipe, which align with each other, as indicated at a² in Fig. 1.

The pipes A and B are brazed together with their openings in juxtaposition. Communication is thus established from the distributing-pipe B directly to each portion of the spiral A. This allows a very effective distribution, and the different portions of the burner-pipe A being all in communication any greater pressure which tends to be near 70 the center is distributed through the pipes longitudinally. This preserves the pressure 75 evenly therein and prevents the pressure running down near the outer portion enough so that the flame may snap back into the admission-tube.

The admission-tube is designated C. It lies beneath the burner A and communicates with the center of the distributing-pipe B. It is to be understood that in use a nozzle (not 85 shown) discharges gas into the tube C, allowing air to pass around the jet thus formed, as is usual with gasoline-burners.

The burner is carried within a sheet-metal shell D, which surrounds it and rises to any 90 height desired. On the inner side of this shell on opposite sides are riveted vertical cross-plates D'. The projecting ends of the distributing-pipe B occupy central openings in these cross-plates, and the admission-tube 95 C occupies a corresponding opening in the

shell itself at d . Thus the burner is rigidly held in place by very simple and inexpensive means.

I claim—

- 5 1. A gas-burner consisting of a continuous coiled pipe perforated on its upper side and intercepted on its under side by a distributing-pipe communicating therewith at a plurality of points, substantially as described.
- 10 2. In a gas-burner, a distributing-pipe consisting of a tube closed at its ends, an admission-tube communicating substantially with the center of the distributing-pipe, and a spiral burner-tube closed at its ends and crossing the distributing-pipe and communicating with it on both sides of the center of the spiral, substantially as described.
- 15 3. In a gas-burner, in combination, a continuous coiled burner-pipe, a transverse distributing-pipe under said burner-pipe, said burner-pipe communicating with the distributing-pipe at each point of contact between the two, substantially as described.
- 20 4. In a gas-burner, in combination, a distributing-tube consisting of a pipe closed at its ends, an admission-tube communicating therewith, and a burner-pipe above the distributing-tube consisting of a continuous coiled pipe communicating with the distributing-tube at numerous points and having burner-openings on its upper side, said coiled pipe being brazed to the distributing-pipe, substantially as described.
- 25 5. A gas-burner pipe consisting of a coiled burner, a cross-pipe beneath the burner-pipe and extending beyond it, said two pipes communicating, portions, and a shell surround-

ing the burner-pipe and having a pair of plates within it through which the ends of the cross-pipe project, substantially as described.

6. A gas-burner consisting of a distributing-pipe closed at its ends, an admission-pipe communicating with the distributing-pipe intermediate of its ends and at an angle thereto, and a burner-pipe above the admission-pipe and distributing-pipe and communicating with said distributing-pipe, said distributing-pipe and admission-pipe extending beyond the burner-pipe, combined with a shell surrounding the gas-burner and carrying the same by means of openings through which the ends of the distributing-pipe and the admission-pipe project, substantially as described.

7. In a gas-burner, in combination, a spiral pipe closed at its ends and having burner-openings on its upper side, a straight distributing-pipe across the under side of the spiral closed at its ends and communicating with the spiral where it crosses the same, an admission-pipe at right angles to the straight pipe communicating with the center thereof, and a shell surrounding and carrying the spiral pipe having an opening through which the admission-pipe projects, substantially as described.

In testimony whereof I hereunto affix my signature in the presence of two witnesses.

WORTHY CHANNING BUCKNAM.
